AWNING ENCLOSURE

Clyde D. Lowry and Paul E. Spahn, Toledo, Ohio,
assignors to Libbey-Owens-Ford Glass Company,
Toledo, Ohio, a corporation of Ohio

Application August 23, 1937, Serial No. 160,370

2 Claims. (Cl. 268—1)

The present invention relates to awnings and their mountings and has for its primary object the provision of an improved enclosure for the awning when in retracted or rolled up position which will not only add to the pleasing and attractive appearance of the building structure equipped with the awning, but which will also serve to protect the awning from the weather when not in use.

Another important object of the invention is the provision of an enclosure which will completely conceal the awning from view when in retracted or rolled up position, and which embodies a hinged cover plate or flap together with novel means for effecting the opening and closing thereof; said flap actuating means being mounted in said enclosure and hidden from view when the said flap is closed.

Another important object of the invention is the provision of an awning enclosure of the above character including a novel type of hinge for mounting the flap which will afford a wide range of movement to the flap; eliminate the necessity for the usual pintle; be of pleasing appearance, practically unnoticeable, and protected from dirt, rain, etc.

Other objects and advantages of the invention will become more apparent during the course of the following description, when taken in connection with the accompanying drawings:

In the drawings, wherein like numerals are employed to designate like parts throughout the same:

Fig. 1 is a front view of a building structure such as a store front, having associated therewith an awning enclosure constructed in accordance with the invention;

Fig. 2 is a vertical sectional view through the awning enclosure taken substantially on line 2—2 of Fig. 1;

Fig. 3 is a sectional view taken substantially on line 3—3 of Fig. 2;

Fig. 4 is a sectional view of the hinge for the cover plate or flap;

Fig. 5 is a vertical detail sectional view of the flap actuating means taken substantially on line 5—5 of Fig. 2; and

Fig. 6 is a similar view showing the actuating means moved into flap opening position.

With reference particularly to Fig. 1, there is illustrated, by way of example, a building structure such as a store front comprising the two spaced display windows A and B above which is provided an awning enclosure C, constructed in accordance with the invention, and in which is

mounted the customary roller type awning, said awning being completely received within the enclosure when in rolled up or retracted position and thereby concealed from view. It will, of course, be readily appreciated that the present invention may be employed in conjunction with any desired type of store front or window.

As best shown in Fig. 2, the awning enclosure C is mounted in an opening D in the building wall E. The enclosure proper comprises a channel 10, which is set back from the face of the building, and the forwardly extending bottom plate 11 and top plate 12 secured to the respective flanges of the channel 10. The bottom and top plates 11 and 12 are provided at their forward ends with downwardly and upwardly extending flanges 13 and 14 respectively which conform to and harmonize with the front of the building. The front of the enclosure is closed by a cover plate or flap 15 hinged at its upper end 16 to the top plate 12 by means of the improved type of hinge, designated in its entirety by the numeral 16 and which will be hereinafter more specifically described. The flap 15 is provided at its lower end with an inturned flange 17 which is adapted to be received within a channel 18 formed in the bottom plate 11 when the said flap is swung to closed position, as indicated in full lines in Fig. 2.

The roller 19, upon which the awning 20 is wound, extends longitudinally within the enclosure and is suitably journaled in the opposite ends thereof. The awning 20 is attached at its free end to the awning pole 21 and when the awning is in wound or retracted position, the awning pole 21 is also received in the enclosure. Suitable means, not shown, but which are well-known in the art, may be employed to effect the raising and lowering of the awning, so that a detailed showing and description of such means is not thought to be necessary.

As best shown in Fig. 4 the hinge 16 is formed of two hinge sections 22 and 23 pivotally associated with one another and carried by the top plate 12 and flap 15 respectively. The hinge section 22 comprises a strip 22' of arcuate or semi-circular formation attached at its upper end to the top plate 12 by a web 24 and provided at its lower end with an upwardly bent flange 25 terminating in a cylindrical bead 26. The hinge section 23 also comprises a strip 23' of arcuate or semi-circular formation oppositely disposed with respect to the strip 22' and secured at its lower end to the flap 15. Formed at the upper end of the strip 23' is an inwardly bent flange 27

27 which terminates in a semi-cylindrical bead
 28 which is received between the arcuate strip
 22' and bead 26, being supported upon the lat-
 ter, which serves as a bearing therefor. The bead
 28 conforms in curvature to the inner surface of
 the strip 22' and outer surface of bead 26, so
 that upon swinging movement of the flap 15, the
 said bead 28 will pivot upon the said bead
 26. In Fig. 4, the position of the hinge sections
 10 22 and 23 is shown in full lines when the flap 15
 is closed and in broken lines when said flap is
 open. As will be apparent, this type of hinge
 is very inconspicuous and will in no way detract
 from the appearance of the enclosure. More-
 over, the movable parts of the hinge are effec-
 tively protected from dirt, rain, etc. In addition,
 the hinge is of extremely simple construc-
 tion and eliminates the necessity for the usual
 pintle.

20 The invention also contemplates the provision
 of novel means for effecting the opening and
 closing of the flap 15, said means being mounted
 in the enclosure and concealed from view but
 operated from a convenient point exteriorly of
 25 said enclosure. To this end, there is arranged
 in the upper end of the enclosure and adjacent
 the flap 15, a longitudinally extending actuating
 or push bar 29, said bar extending substantially
 the entire length of the enclosure and slidably
 30 carried by a plurality of substantially U-shaped
 brackets 30 secured to the underside of the top
 plate 12. The push bar 29 is provided adjacent
 one end thereof with a series of rack teeth 31
 with which is adapted to mesh a pinion 32 fixed
 35 to the upper end of a vertical shaft 33.

As illustrated in Fig. 1, the shaft 33 may be
 arranged at one side of the store front and can
 pass downwardly through the wall of the build-
 ing, being operated at its lower end by a crank
 40 34 insertable by the operator through an open-
 ing 35 in the said wall. The opening 35 can be
 normally closed by a suitable plate if desired.
 The vertical shaft 33 is journaled at its upper
 45 end in the top plate 12 and the pinion 32 may
 be housed in a casing 36.

Carried upon the under side of the push bar
 29, preferably at regularly spaced intervals along
 the length thereof, are a plurality of cam or
 50 wedge blocks 37 and these blocks are adapted,
 upon longitudinal sliding movement of the push
 bar, to engage the inwardly extending, horizontal
 lever arms 38 carried by the flap 15. The bot-
 tom surface of each wedge block 37 tapers long-
 55 tudinally from the end *a* to the end *b* thereof
 (Figs. 5 and 6) and likewise tapers transversely
 from the inner side edge *c* to the outer side edge
d. Furthermore, the degree of transverse taper
 gradually decreases from the end *a* to the end *b*
 60 of the block, so that at the end *b* the block ter-
 minates in a relatively thin flat edge. The
 amount of transverse taper gradually increases
 toward the end *a* as the thickness of the block
 also increases. This particular shape of wedge
 65 or cam block is of advantage in that, as the
 blocks engage the lever arms 38 to swing the flap
 15 open, the said lever arms will always bear upon
 a relatively wide, flat surface on the blocks, there-
 by resulting in a sturdier, more efficient con-
 struction as well as reducing the wear on the
 70 said blocks 37 and lever arms 38. In other words,
 the transverse taper of the cam or wedge blocks
 corresponds to the arc through which the lever
 arms 38 is swung during the opening and clos-
 ing of the flap 15.

75 In operation, when the awning 28 is not being

used, it is wound upon the drum 19 whereupon
 the entire awning as well as the awning pole 21
 will be completely contained within the enclosure
 and concealed from view by the flap 15. When
 the flap is closed, the push bar 29 is moved to
 the left in Fig. 1, so that the cam or wedge blocks
 5 37 will be out of engagement with the lever arms
 38 as shown in Fig. 5. When it is then desired
 to use the awning, the operator rotates the shaft
 10 33 to revolve the pinion 32 carried at the upper
 end thereof. The pinion, meshing with the rack
 teeth 31, will move the push bar 29 to the right
 in Fig. 1, and when this is done, the blocks 37
 15 engaging the upper surfaces of the lever arms 38
 will force the said lever arms downwardly and
 as a consequence swing the flap 15 outwardly
 to open position, the swinging movement of the
 flap being permitted by the hinge construction 16
 above described. When the flap has been moved
 to open position, the wedge blocks 37 will be
 20 disposed above the lever arms, as shown in Fig. 6,
 and will be retained in such position until it is
 desired to close the flap, at which time the shaft
 25 33 is turned in the opposite direction to move
 the push bar 29 to the left in Fig. 1, whereupon
 the blocks 37 will be moved out of engagement
 with the lever arms 38 and the flap 15 permitted
 to fall to closed position by gravity.

As disclosed, the awning enclosure herein pro-
 30 vided is designed primarily for use in connection
 with metal store front constructions, but it will
 be readily appreciated that it is not limited to
 any particular use or to the use of any special
 materials. This type of enclosure not only ef-
 35 fectively protects the awning, when in retracted
 position, from exposure to the weather but also,
 by concealing the awning when not in use, adds
 greatly to the appearance of the store front. The
 style of the enclosure, including the size and
 40 shape thereof, can be made to harmonize with
 and fit into the general appearance and archi-
 tecture of the store front. Even when the awn-
 ing is in use, the flap 15, maintained in an in-
 clined position, will still add to the appearance
 45 of the store front as it will conceal to a large
 extent the drum around which the awning is
 wound, as well as the actuating means for the
 flap. Furthermore, the flap, when in such pos-
 50 ition, will also give substantially full protection
 of the working parts inside the enclosure against
 the weather and dust and dirt.

It is to be understood that the form of the
 invention herewith shown and described is to be
 taken as the preferred embodiment of the same,
 and that various changes in the shape, size and
 55 arrangement of parts may be resorted to without
 departing from the spirit of the invention or the
 scope of the subjoined claims.

We claim:

1. An enclosure for awnings and the like hav-
 ing an opening, a flap for said opening hinged at
 its upper end, a lever arm carried by said flap, a
 push bar extending longitudinally within said
 enclosure and mounted for horizontal sliding
 movement, and a cam member carried by said
 60 push bar and engaging said lever arm upon slid-
 ing movement of the said push bar for effecting
 the opening of said flap, said cam member com-
 prising a block tapering from one end to the
 opposite end thereof and also transversely from
 65 its inner edge to its outer edge.

2. An enclosure for awnings and the like hav-
 ing an opening, a flap for said opening hinged
 at its upper end, a lever arm carried by said flap,
 a push bar extending longitudinally within said
 70

- enclosure and mounted for horizontal sliding movement, rack teeth carried by said push bar, a pinion meshing with said rack teeth, a cam member carried by said push bar and engaging said lever arm upon sliding movement of the said push bar for effecting the opening of said flap, and means operable from a point exteriorly of said enclosure for effecting the rotation of said pinion to cause sliding movement of the push bar, said cam member comprising a block tapering from one end to the opposite end thereof and also transversely from its inner edge to its outer edge. 5
